WIND VANE

Alden H. Simpson, 54 Pine Grove St.
Springfield, Mass. 01119

Filed Sept. 18, 1974, Ser. No. 507,012

Term of patent 14 years

Int. Cl. D11—02

U.S. Cl. D35—1

FIG. 1

FIG. 2

FIG. 3

FIG. 1 is a perspective view of a wind vane embodying my new design;

FIG. 2 is a top plan view thereof; and

FIG. 3 is a side elevational view thereof.

I claim:

The ornamental design for a wind vane, as shown.
